HEAT EXCHANGE TUBING

Irving H. Cohler, Chicago, Ill.

Application July 2, 1949, Serial No. 102,791

6 Claims. (Cl. 257—242)

1

My invention relates to heat exchange apparatus and is particularly concerned with heat exchange tubing, particularly for use in liquid coolers and heaters, condensers, heating and cooling coils, and heat exchangers generally.

Various types of heat exchange equipment, and tubing for use or in connection therewith, have heretofore been proposed and gone into widespread use in the art. By and large, these have reasonably adequately met the needs of the specific industries where they have been used. In certain situations, however, existing equipment has failed satisfactorily to meet the problems presented and it is to the solution of said problems upon a practical basis to which my present invention is directed.

In various types of installations, it is essential to meet certain standards of safety without at the same time undue sacrifice of heat exchange efficiency. A typical case involves water cooling apparatus where the possibility of contamination of the water by leakage from the piping carrying the refrigerating or cooling medium must be reduced to a practical minimum without, however, unduly impairing the heat transfer efficiency of the system. Efforts heretofore made satisfactorily to meet this situation have failed, generally because of the high cost of the special equipment proposed or because of the low efficiency of heat transfer of other suggested equipment.

In general, my invention comprises the production of novel heat exchange tubing comprising at least two individual metal tubes which may be of the same or different cross sectional size and shape, made of a metal of good heat conductivity, for example, copper, copper alloys, stainless steel, or the like, said tubes being of generally rounded cross section, said tubes being disposed in parallel longitudinal relationship with each other. For most purposes, only two individual tubes are utilized and, most advantageously, they are of conventional type, namely, their inner and outer peripheries being circular in cross section. For certain types of heat exchange problems, three or more individual metal tubes may be utilized and, in such cases, all of said tubes are disposed in longitudinal or parallel relationship with each other. The outer surfaces of the two tubes, or the outer surfaces of the adjacent tubes in any series of more than two tubes, are in contact with each other over only a portion, particularly over only a small fraction, of their surface areas and the adjacent tubes are united to each other over only a small area in immediate juxtaposition to their areas of contact. In the case of tubes the

2

outer peripheries of which are circular in cross section, the contact between such tubes, if they are of equal diameter, is theoretically a line contact although, as a practical proposition, it is greater than that. In any event, the area of contact between adjacent tubes is small in relation to the totality of their external surfaces.

The tube assembly, described above, is encompassed by metallic banding of good thermal conductivity and it is particularly desirable that said banding be bonded to said tubes. The banding may be made of any metal of good or reasonably good thermal conductivity as, for example, copper, copper alloys, stainless steel, or the like. The banding may take the form of round or flat wire, of relatively wide individual sheets or preformed tubes, but it is particularly desirable that it be of flat strip material. The banding may take various forms, as described hereafter in greater detail in conjunction with the drawing, and it should contact the tubes over a substantial area, preferably from about 50% to about 75%, of their external surfaces. It serves to provide a high degree of heat transfer surface from one tube to another with a substantially minimum amount of physical contact between the individual tubes. The construction is such as to leave oppositely disposed air spaces defined by portions of the outer periphery of each of said tubes and the inner surfaces of said banding.

The invention will be particularly clearly understood in the light of the accompanying drawing which illustrates various embodiments of my invention and wherein

Fig. 1 is an elevational view of one embodiment of heat exchange tubing made in accordance with my invention;

Fig. 2 is an elevational view of a second embodiment of my invention;

Fig. 3 is an elevational view of a third embodiment of my invention;

Fig. 4 is an elevational view of a fourth embodiment of my invention;

Fig. 5 is a cross sectional view taken along the line 5—5 of Fig. 1.

Fig. 6 is a cross sectional view of another embodiment of my invention;

Fig. 7 is a cross sectional view of still another embodiment of my invention;

Fig. 8 shows heat exchange tubing, made in accordance with my invention, wound into a coil; and

Fig. 9 shows a still further modified embodiment utilizing certain features of my invention.

In Figs. 1 and 5, the tubes 10 and 11 are shown

disposed in parallel longitudinal relationship to each other and united or bonded together as shown at 12 and 13. The union or bonding may be continuous along the length of the tubes or it may be at spaced intervals. Two lines of bonding may be employed or the bonding may be along only one line. It is most advantageous that the bonding be along two lines, as shown, that it be continuous or substantially so. The bonding may be accomplished by welding, by means of solder or like materials or in any other suitable manner. In any event, it will be noted that the tubes are united to each other over only a very small area immediately adjacent to their areas of contact. A continuous flat metallic strip 14 is wound helically around the tubes to form an encompassing metallic banding, the windings of said banding being slightly spaced from each other to provide apertures or spaces 16. As shown more particularly in Fig. 5, the banding 14 is bonded to the tubes at 17, 18, 19 and 21. This bonding need not be at all of said areas and, as described in connection with the bonding at 12 and 13, it may be continuous or discontinuous along the width of each winding of said banding. It is particularly desirable that the bonding area encompass substantially the entire surface between the banding and those areas of the tubes with which said banding is in contact. This may be accomplished by welding, soldering or like operations. The construction described provides oppositely disposed separate air spaces 22 and 23 defined by portions of the outer periphery of each of the tubes and the inner surfaces of said banding. Any leakage in either of the tubes 10 or 11 would be readily manifested through apertures or spaces 16.

In Fig. 2, the construction is similar to that of Figs. 1 and 5 except that the metallic banding 24 is helically wound in such a manner as to leave no space between the successive windings, and holes or apertures 26 are provided in said banding in lieu of spaces 16 in the embodiment of Figs. 1 and 5.

Fig. 3 shows a construction wherein individual metallic bands 27, spaced from each other, are utilized to form the encompassing metallic banding, and Fig. 4 shows a construction similar to that of Fig. 3 except that the individual bands 28 are not spaced from each other and are provided with holes or apertures 29.

In Figs. 3 and 4, instead of using a plurality of individual bands, I may employ a single band made from a single, relatively wide sheet of copper, copper alloy or other metal of good heat conductivity. The single sheet of metal may be wrapped around the tubing and suitably bonded thereto to form the encompassing metallic banding, or the banding may comprise a preformed tube which may be slipped over the tubing and suitably bonded thereto, as described above.

Fig. 6 shows an embodiment of my invention wherein three tubes, 31, 32 and 33, are employed, the adjacent tubes of which are bonded to each other at 34, 36, 37 and 38. The encompassing metallic banding 39 may take any of the illustrative forms shown in Figs. 1 to 5, inclusive, and bonding may be effected at several areas as, for example at 41, 42, 43 and 44. In the embodiment of Fig. 6, it will be noted that the banding 39 is crimped inwardly adjacent the air spaces, preferably at all four points 45, 46, 47 and 48. This crimping may be accomplished by any suitable tool or equipment and serves to improve the thermal efficiency of the unit. It

will be understood that, if desired, this crimping feature may be employed in any of the embodiments of Figs. 1 to 5, inclusive.

Fig. 7 shows a construction wherein the tubes 49 and 51 are of generally elliptical configuration and are in contact with each other along a line drawn through their major or transverse axes. Bonding and banding may be similar to that described above.

In Fig. 8, I show the tubular construction of my invention arranged in the form of a coil 52. In this connection, it should be noted that the coil may be made in various ways and by various sequences of steps. The use of such coils is especially advantageous in various heat exchange arrangements and such coils comprise an important, though limited, embodiment of my invention.

In the construction of Fig. 9, it will be noted that each convolution of the coil 53 is not provided with separate banding. Rather, the banding 54 is wound or wrapped around the pre-formed coil of the two or more individual tubes bonded together as described above, or bonded together at any other suitable stage in the manufacture of the finished coil, and said encompassing metallic banding is united or bonded to said tubes and preferably crimped as shown at 55.

While my invention has been described in detail, no unnecessary limitations should be read thereinto, the scope of the invention being set out in the appended claims.

What I claim as new and desire to protect by Letters Patent of the United States is:

1. A prefabricated heat exchange tubing structure comprising at least two individual metal tubes of generally rounded cross section, all of said metal tubes being disposed in essentially a single plane and in parallel longitudinal relationship with each other, the outer surfaces of only the adjacent metal tubes being in contact with each other over substantially only a line contact, each of said metal tubes being metallically and rigidly bonded to its adjacent metal tube over only a small area immediately adjacent their lines of contact to provide a first path of good thermal conductivity between the adjacent metal tubes and to give rigidity to the heat exchange tubing structure, and metallic banding of good thermal conductivity encompassing said metal tubes, contacting said metal tubes over a substantial area of their external surfaces and being metallically and rigidly bonded to said metal tubes to provide a second path of good thermal conductivity between the metal tubes and also to give rigidity to the heat exchange tubing structure, there being oppositely disposed separate air spaces defined by portions of the outer surfaces of each of said metal tubes and the inner surfaces of said metallic banding for collecting fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding having apertures communicating with said air spaces so that leakage from said metal tubes into any of said air spaces upon rupture of any of said metal tubes may be readily detected through said apertures from the exterior of the prefabricated heat exchange tubing structure.

2. A prefabricated heat exchange tubing structure comprising at least two individual metal tubes of generally rounded cross section, all of said metal tubes being disposed in essentially a single plane and in parallel longitudinal relationship with each other, the outer surfaces of only the adjacent metal tubes being in contact with each other over substantially only a line contact, each of said metal tubes being metallically and rigidly bonded to its adjacent metal tube over only a small area immediately adjacent their lines of contact to provide a first path of good thermal conductivity between the adjacent metal tubes and to give rigidity to the heat exchange tubing structure, and metallic banding of good thermal conductivity encompassing said metal tubes, being partially crimped about said metal tubes and contacting said metal tubes over a substantial area of their external surfaces and being metallically and rigidly bonded to said metal tubes to provide a second path of good thermal conductivity between the metal tubes and also to give rigidity to the heat exchange tubing structure, there being oppositely disposed separate air spaces defined by portions of the outer surfaces of each of said metal tubes and the inner surfaces of the crimped portions of said metallic banding for collecting fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding having apertures communicating with said air spaces so that leakage from said metal tubes into any of said air spaces upon rupture of any of said metal tubes may be readily detected through said apertures from the exterior of the prefabricated heat exchange tubing structure.

3. A prefabricated heat exchange tubing structure comprising at least two individual metal tubes of generally rounded cross section, all of said metal tubes being disposed in essentially a single plane and in parallel longitudinal relationship with each other, the outer surfaces of only the adjacent metal tubes being in contact with each other over substantially only a line contact, each of said metal tubes being metallically and rigidly bonded to its adjacent metal tube over only a small area immediately adjacent their lines of contact to provide a first path of good thermal conductivity between the adjacent metal tubes and to give rigidity to the heat exchange tubing structure, and metallic banding of good thermal conductivity encompassing said metal tubes, contacting said metal tubes over a substantial area of their external surfaces and being metallically and rigidly bonded to said metal tubes to provide a second path of good thermal conductivity between the metal tubes and also to give rigidity to the heat exchange tubing structure, there being oppositely disposed separate air spaces defined by portions of the outer surfaces of each of said metal tubes and the inner surfaces of said metallic banding for collecting fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding consisting of a relatively flat and narrow metallic band helically wound around said tubes and having holes spaced therealong to provide apertures communicating with said air spaces so that leakage from said metal tubes into any of said air spaces upon rupture of any of said metal tubes may be readily detected through said apertures from the exterior of the prefabricated heat exchange tubing structure.

wound around said tubes with the winding of said metallic band being slightly spaced from each other to provide apertures communicating with said air spaces so that leakage from said metal tubes into any of said air spaces upon rupture of any of said metal tubes may be readily detected through said apertures from the exterior of the prefabricated heat exchange tubing structure.

4. A prefabricated heat exchange tubing structure comprising at least two individual metal tubes of generally rounded cross section, all of said metal tubes being disposed in essentially a single plane and in parallel longitudinal relationship with each other, the outer surfaces of only the adjacent metal tubes being in contact with each other over substantially only a line contact, each of said metal tubes being metallically and rigidly bonded to its adjacent metal tube over only a small area immediately adjacent their lines of contact to provide a first path of good thermal conductivity between the adjacent metal tubes and to give rigidity to the heat exchange tubing structure, and metallic banding of good thermal conductivity encompassing said metal tubes, contacting said metal tubes over a substantial area of their external surfaces and being metallically and rigidly bonded to said metal tubes to provide a second path of good thermal conductivity between the metal tubes and also to give rigidity to the heat exchange tubing structure, there being oppositely disposed separate air spaces defined by portions of the outer surfaces of each of said metal tubes and the inner surfaces of said metallic banding for collecting fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding consisting of a relatively flat and narrow metallic band helically wound around said tubes and having holes spaced therealong to provide apertures communicating with said air spaces so that leakage from said metal tubes into any of said air spaces upon rupture of any of said metal tubes may be readily detected through said apertures from the exterior of the prefabricated heat exchange tubing structure.

5. A prefabricated heat exchange tubing structure comprising at least two individual metal tubes of generally rounded cross section, all of said metal tubes being disposed in essentially a single plane and in parallel longitudinal relationship with each other, the outer surfaces of only the adjacent metal tubes being in contact with each other over substantially only a line contact, each of said metal tubes being metallically and rigidly bonded to its adjacent metal tube over only a small area immediately adjacent their lines of contact to provide a first path of good thermal conductivity between the adjacent metal tubes and to give rigidity to the heat exchange tubing structure, and metallic banding of good thermal conductivity encompassing said metal tubes, contacting said metal tubes over a substantial area of their external surfaces and being metallically and rigidly bonded to said metal tubes to provide a second path of good thermal conductivity between the metal tubes and also to give rigidity to the heat exchange tubing structure, there being oppositely disposed separate air spaces defined by portions of the outer surfaces of each of said metal tubes and the inner surfaces of said metallic banding for collecting fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding consisting of a relatively flat and narrow metallic band helically wound around said tubes and having holes spaced therealong to provide apertures communicating with said air spaces so that leakage from said metal tubes into any of said air spaces upon rupture of any of said metal tubes may be readily detected through said apertures from the exterior of the prefabricated heat exchange tubing structure.

of said metallic banding for collecting fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding consisting of a series of individual relatively flat and narrow metallic bands encompassing said metal tubes and spaced slightly from each other to provide apertures communicating with said air spaces so that leakage from said metal tubes into any of said air spaces upon rupture of any of said metal tubes may be readily detected through said apertures from the exterior of the prefabricated heat exchange tubing structure.

6. A prefabricated heat exchange tubing structure comprising at least two individual metal tubes of generally rounded cross section, all of said metal tubes being disposed in essentially a single plane and in parallel longitudinal relationship with each other, the outer surfaces of only the adjacent metal tubes being in contact with each other over substantially only a line contact, each of said metal tubes being metallically and rigidly bonded to its adjacent metal tube over only a small area immediately adjacent their lines of contact to provide a first path of good thermal conductivity between the adjacent metal tubes and to give rigidity to the heat exchange tubing structure, and metallic banding of good thermal conductivity encompassing said metal tubes, contacting said metal tubes over a substantial area of their external surfaces and being metallically and rigidly bonded to said metal tubes to provide a second path of good thermal conductivity between the metal tubes and also to give rigidity to the heat exchange tubing structure, there being oppositely disposed separate air spaces defined by portions of the outer surfaces of each of said metal tubes and the inner surfaces of said metallic banding for collecting

fluid from said metal tubes in the event of rupture of any of said metal tubes within the confines of said metallic banding and adjacent the air spaces and for effectively preventing intermingling of the fluids in said metal tubes upon such rupturing of any of said metal tubes, said encompassing metallic banding consisting of a series of individual relatively flat and narrow metallic bands encompassing said metal tubes, each said metallic band being provided with holes spaced therealong to provide apertures communicating with said air spaces so that leakage from said metal tubes into any of said air spaces upon rupture of any of said metal tubes may be readily detected through said apertures from the exterior of the prefabricated heat exchange tubing structure.
